UNITED STATES PATENT OFFICE

GUY W. BLACKBURN, OF ELGIN, ILLINOIS

WRITING INSTRUMENT

Application filed May 15, 1925. Serial No. 30,488.

My invention relates to a means for writing and particularly to a means for writing upon combustible substances by the local application of heat. Other objects will appear from time to time throughout the course of the specification and claims.

10 My invention is illustrated more or less diagrammatically in the accompanying drawings, wherein—

Figure 1 is a longitudinal section through the writing implement;

Figures 2 and 3 are sectional details of variations;

15 Figure 4 is a side elevation with parts broken away of a variant form;

Figure 5 is an axial section through a variant form of instrument.

Like parts are indicated by like characters throughout the specification and drawings.

20 Referring to Figure 1, A is any suitable body or casing of conducting material herein shown as cylindrical. One end is screw threaded as at A¹ to receive the cap A². The opposite end is inwardly turned as at A³ and 25 provided with a screw threaded sleeve A⁴ forwardly projecting therefrom, said portion being screw threaded both internally and externally.

B is any suitable battery or series of batteries having a forward exposed contact B¹ and being forwardly thrust for example by the spring B² compressed against the cap A². The cylindrical sides of the battery are perfectly covered by an insulating material B³.

30 35 Mounted in the interior of the cylinder A and adapted to support a resistance coil or wire B⁵ having a plurality of contacts B⁶, is a clip B⁴ of insulating material. The wall of the cylinder is longitudinally slotted thereabove, 40 as at B⁷, the slot being closed by the slide B⁸ controlled by the handle B⁹. B¹⁰ is a contact on the slide opposed to the contacts B⁶ associated with the resistance coil.

C is any suitable plug or supporting means 45 of insulating material internally screw threaded in the sleeve A⁴ and having an interior contact C¹ opposed to the battery contact B¹. The plug is apertured to permit the passage therethrough of the wire C² which 50 may be suitably covered or insulated and

which extends inwardly from the plug, and is in circuit with the resistance wire B⁵.

D is an inner plug screw threaded as at D¹ into the central aperture of the plug C and axially apertured to permit the passage of the wire D² extending through to the contact C¹. The wires D² and C² are in circuit and included in their circuit is any suitable resistance element herein illustrated as the coiled wire D³. This wire is located in the hollow D⁴ of the enlarged tip D⁶ of the plug D. This plug or its tip is preferably composed of material adapted for the ready transmission of heat.

E is any suitable cap or shield internally screw threaded as at E¹ and upon the sleeve A⁴ and adapted to surround all but the extreme tip of the member D⁵. It is preferably of material adapted to serve as an insulant against the transmission both of electricity and heat. Another function of the insulated cap E is to prevent the tip D⁵ burning deep enough to catch in the paper or to burn through more than one sheet.

Referring to Figure 2, a slightly variant 75 form of plug corresponding to the plug C is illustrated.

G is the body of the plug apertured to permit the passage of the wires G¹ G² in circuit with the resistance member G³, herein shown as a bent wire of somewhat greater cross section than the wires G¹ G². The plug G is shaped to conform to the interior of the shield E and is adapted to be screw threaded into the sleeve A⁴.

The corresponding plug H of Figure 3 terminates in a hemispherical surface H¹ upon which is mounted the hemispherical cap H² of resistance material. H³ H⁴ are wires in circuit therewith whereby it may be put in 90 circuit with the battery or other power source.

Referring to Figure 4, a form of pen is illustrated in which the current from a fixed power source may be employed.

J is the cylindrical body of the pen having 95 connected thereto the flexible cord J¹ containing the inleading and outleading wires J² J³. Any suitable tip J⁴ is employed covered by the shield J⁵. J⁶ is a switch or contact adapted to be engaged by the stud J⁷ 100

on the manually controllable slide J^8 it being understood that when the contacts J^6 and J^7 are closed the current flows through the tip J^4 or any suitable resistance member adapted to heat it.

Referring to Figure 5, K is the cylindrical body of the pen and K^1 the forward protecting shield. Screw threaded into it is the plug K^2 with a central contactor element K^3 opposed to the battery contact K^4 . The pen nib K^6 is placed in contact therewith. Mounted on the insulating plug K^2 is the spring or contact member K^6 adapted to contact the sleeve K^7 and thus to be in circuit with the casing K , which is of conducting material. K^6 and K^6 are so placed and proportioned that only when pressure is actually exerted upon the pen are they in contact and is the circuit closed. Their opposed tips are preferably of resistant material which, with the closing of the gap between the two, results in the immediate development of local heat in response to pressure upon the pen. The material employed is preferably heat resistant in order that it may not be destroyed or fused as a result of the heat so generated.

It will be evident that while I have shown in my drawings an operative device still many changes might be made in the size, shape, number and disposition of parts without departing materially from the spirit of my invention and I wish, therefore, that my showing be taken as in a sense diagrammatic.

The use and operation of my invention are as follows:

In making permanent records it is desirable to have the mark made by the recording instrument as imperishable as possible. It should be able to resist both the chemical and physical changes caused by time. It is particularly important, in connection with documents or records involving the payment of sums of money, that the indicating marks be difficult to change or remove. In my apparatus for making such records I make an impression on a combustible or a carbonizable substance by the local application of heat. The surface of the paper or their receiving medium is chemically changed, and the mark is made without the superposition of any additional substance. Pencil marks and ink marks, which are merely bodies of foreign material resting upon an unmodified surface, may be removed by erasure or by chemical means and in many cases may be removed without leaving any trace of their existence. My method is actually to transform the chemical nature of the surface of the paper or record. Writing on paper, for example, the local application of heat transforms that part of the paper exposed to it, and turns or drives out certain of the component parts. In effect a more or less thin inlay of carbon is left, the top of the carbon being flush with the surface of the paper. The carbon is, of

course, of different color than the surrounding body of the paper and may be as readily legible as an ink mark. If it is removed it leaves an indentation of the paper. Under some circumstances it may be advantageous to make the impression so deep as practically to pass through the paper. An attempt to remove the impression, in such case, leaves the original marks in the form of perforations, and alteration thereof is peculiarly hard.

I am able to write fine lines by this method, since the area exposed to the heat is extremely small, the writing tip being insulated except at a single point. Furthermore, as the paper chars, and the thin layer of carbon forms, or is separated from the body of the paper by the driving off of the other components, the carbon so formed is an admirable insulant against heat and itself limits the spread of the charring. By varying the chemical composition of the paper written upon, it is possible to vary the color of the impression, since some papers char brown and others black.

I may make the closing of the heat circuit respond directly to pressure on the pen, as shown in Figure 5 or I may provide positive means for varying the heat, as shown in Figure 1. In the latter case the resistance B^5 cuts out part of the current which would otherwise pass to the resistance D^8 , when the contact B^{10} is positioned over the contact B^6 . If it is positioned as shown in the figure, the resistance B^5 is cut out and the full current of the battery passes through the element D^8 . Under some circumstances this reaction is important since the faster the writing the greater the heat and the current necessary to make a legible impression. In Figure 4 I illustrate a form wherein the circuit used may be taken from a fixed power source, for example, the ordinary house circuit.

I claim:

1. In a pen, a hollow handled casing, adapted to contain a battery, a resistance element mounted on said casing, a circuit including a resistance element and said battery, and means for making and breaking it, adapted to close said circuit during the actual writing operation comprising a flexible nib and a contact opposed thereto, said nib adapted to be moved against said contact in response to the pressure of writing.

2. In a pen, a handle member, a resistance element mounted thereon, a source of electric energy therefor, a circuit including said resistance element and said source of energy, and means for making and breaking it adapted to close said circuit during the actual writing operation comprising a flexible nib and a contact opposed thereto, said nib adapted to be moved against said contact in response to the pressure of writing.

3. In combination, a pen and an electric circuit connected therewith, a point comprising a resistance element and means for pass-

ing current through said circuit and through said pen, said circuit adapted to be closed in response to the pressure of writing.

4. In an instrument for making permanent records upon a combustible surface, an element and means for heating it, a shield, resistant to the passage of heat, substantially surrounding said element, said shield being penetrated by an aperture of small cross section, the heated element projecting slightly through said aperture, the relative proportions of aperture and heated element being such that a relatively small tilting of the writing instrument suffices to lift the heated element from contact with the opposed surface.

Signed at Chicago, county of Cook, and State of Illinois, this 29th day of April, 1925.

GUY W. BLACKBURN.
